UNITED STATES PATENT OFFICE.

WILLIAM PRELLWITZ, OF EASTON, PENNSYLVANIA, ASSIGNOR TO INGERSOLL-RAND COMPANY, OF NEW YORK, N. Y., A CORPORATION OF NEW JERSEY.

HAMMER-DRILL.

1,078,953.

Specification of Letters Patent. Patented Nov. 18, 1913.

Application filed February 6, 1909. Serial No. 476,500.

To all whom it may concern:

Be it known that I, WILLIAM PRELLWITZ, a citizen of the United States, and resident of Easton, in the county of Northampton and State of Pennsylvania, have invented a new and useful Improvement in Hammer-Drills, of which the following is a specification.

This invention relates to hammer drills and has for its object to provide a novel construction at the front end of the drill, which construction, combined with a hollow drill steel of novel form, will be particularly well adapted for feeding fluid under pressure to the drill steel; fluid tight packings being provided for the pressure fluid feeding chamber, the said chamber and its adjacent parts being located within the front head of the drill.

In the accompanying drawings, Figure 1 represents in side elevation the front end of a hammer drill, with the invention applied thereto, the hollow drill steel being broken away, Fig. 2 is a front end view of the same, Fig. 3 is a detail longitudinal central section through the front end of the hammer drill with its steel and anvil block shown in side elevation, and Fig. 4 is a transverse section taken in the plane of the line A—A of Fig. 3, looking in the direction of the arrows, the drill steel being removed.

The drill cylinder is denoted by 1 and its hollow front head by 2, which front head is held in position by longitudinally extended tie bolts 3. A drill steel receiving chuck 4 is mounted within the cylinder 1 and is provided with an open ended socket 5 angular in cross section to correspond to the striking end of the drill steel. This chuck 40 is interlocked by wings 4*, 4* with the front end of a sleeve 6 also mounted within the cylinder 1. This sleeve 6 is rotated in the usual manner by the reciprocation of the hammer piston, not shown herein, and is 45 provided with an annular interior rib 7 forming a reduced bore for receiving the shank 8 of an anvil block, the head 9 of which block is located in position to engage the striking end of a hollow drill steel 10 which projects beyond the inner end of the chuck 4. The drill steel is provided adjacent to its angular striking end with a cylindrical portion 11. A short tube 12 is mounted within the hollow front head 2 and 55 is spaced from the cylindrical portion 11 of

the drill steel to form an annular pressure fluid feeding chamber 13. This tube 12 is further provided with a circumferential groove 14 which forms an outer pressure fluid feeding chamber, which chamber is in 60 open communication with the inner chamber 13 through one or more transverse holes 15. A fluid pressure supply pipe 16 is engaged with a transverse hole 17 in the hollow front head 2 opposite the outer chamber 14 for bringing the inner chamber 13 into open communication with the pressure fluid supply. The longitudinally arranged axial bore 18 of the hollow drill steel 10 is provided with a transverse hole 19 opening into the chamber 13. A rigid ring 20 is interposed between an interior annular shoulder 21 on the hollow front head 2 and the outer ends of the cylinder, chuck and rotating sleeve. An elastic washer 22 and the base 23 of a cup washer 24 is interposed between the ring 20 and the inner end of the tube 12. An elastic ring 25 and the base 26 of a cup washer 27 are interposed between the end of the front head 2 and the outer end 75 of the tube 12. These cup washers 24, 27, form fluid tight packings between the cylindrical portion 11 of the drill steel and the tube 12 for preventing the escape of the pressure fluid from the chamber 13. The elastic 80 washers 22 and 25 serve as fluid tight packings for preventing the leakage of the pressure fluid from the outer chamber 14.

It will be seen that by the construction and arrangement of the parts as here shown 90 and described, a fluid tight packing is provided which will prevent the escape of the pressure fluid being fed to the drill steel and at the same time ready access may be obtained for the renewal of the several parts. Furthermore, the parts are so arranged that the slight longitudinal reciprocatory movements of the drill steel and its rotation during the operation of the drill, will not interfere with the feed of the pressure fluid to 100 the drill steel.

What I claim is:

1. In combination, a cylinder, a chuck, a hollow front head, a hollow drill steel having a cylindrical portion at the outer end of the chuck, a tube within the front head spaced from said cylindrical portion of the drill steel to form a pressure fluid feeding chamber, means for feeding pressure fluid to said chamber, said drill steel having a 110

passage connecting its bore with said chamber, the said tube having a circumferential groove in open communication with the pressure fluid feeding means and with the 5 said pressure fluid feeding chamber, cup washers interposed between the ends of the said tube and the cylindrical portion of the drill steel to form fluid tight packings for the pressure fluid feeding chamber, and elastic 10 rings interposed between the outer and inner ends of said tube and the front head and outer end of the cylinder, respectively.

2. In combination, a cylinder, a chuck rotatably mounted therein, a hollow front 15 head, a hollow drill steel having a cylindrical portion at the outer end of the chuck, a tube within the front head spaced from said cylindrical portion of the drill steel to form a pressure fluid feeding chamber, 20 means for feeding pressure fluid to said chamber, said drill steel having a passage

connecting its bore with said chamber, the said tube having a circumferential groove in open communication with the pressure fluid feeding means and with the said pressure fluid feeding chamber, cup washers interposed between the ends of the said tube and the cylindrical portion of the drill steel to form fluid tight packings for the pressure fluid feeding chamber, and elastic rings interposed between the outer and inner ends of said tube and the front head and outer end of the cylinder, respectively. 25

In testimony that I claim the foregoing as my invention I have signed my name in 30 presence of two witnesses, this fourth day of February 1909.

WILLIAM PRELLWITZ.
